UNITED STATES PATENT OFFICE.

LEO E. EVSLIN, OF NEW YORK, N. Y.

TOOTHBRAHSH.

1,378,530.

Specification of Letters Patent. Patented May 17, 1921.

Application filed January 23, 1919. Serial No. 272,668.

To all whom it may concern:

Be it known that I, LEO E. EVSLIN, a citizen of the United States, and a resident of the borough of Manhattan, city, county, and 5 State of New York, have invented a certain new and useful Toothbrush, of which the following is a specification.

My invention relates to tooth brushes, and has for its objects to produce such a device 10 in which the brush proper may be separated from the handle for the purpose hereinafter mentioned, and wherein the brush when in position on the handle, will be securely held in position and prevented from rotating 15 relatively to the handle.

A further object of the invention is to provide a structure, of the character herein described, which is extremely simple in construction, reliable and efficient in its purpose, and inexpensive to manufacture.

These and other objects will more fully appear in the following specification and accompanying drawings, considered together or separately.

25 I have illustrated one embodiment of my invention in the accompanying drawings in which like parts in all of the figures are designated by similar reference characters, and in which,

30 Figure 1 is a side elevation of a tooth brush embodying my invention;

Fig. 2 is a longitudinal section of the same;

Fig. 3 is a section taken on the line 3—3 35 of Fig. 2;

Fig. 4 is a similar view of a modification; and

Fig. 5 is a detail view of a further modification.

40 In carrying out my invention, I provide a tubular handle member 1, one end of which carries a nut 2 having a milled head 3, the said nut being rotatable relatively to the handle 1.

45 The opposite end of the handle 1 is provided with a reduced tubular extension 4, the outer extremity of which is bent as at 5.

Carried on the bent end of the extension 4 is a brush member 6. The brush member 50 6 may be of any desired size, shape or material. In Figs. 1, 2 and 3, I have illustrated the brush as composed of a block 7 of soft rubber, one side of which is provided with a plurality of laterally extending cylindrical 55 projections of "bristles" 8. The member 7

is provided with a socket 9 extending partially through it in the longitudinal direction, and a perforation 10 extending from the socket 9 to the other end of the block.

A flexible rod 11 having a head 12 is inserted in the perforation 10 of the block 7 and passed through the socket 9 and through the tubular portion of the handle 1. The end of the rod opposite the head is screw-threaded for engagement with the nut 2. 60 The major portion of the rod is of rectangular cross-section and of ribbon-like form. The rod is preferably of more or less flexible material such as steel, and preferably is given a permanent bend at a short distance 65 from the head end. The bend in the rod and its flexible nature will facilitate the passage of the rod around the bend 5. The head 12, when the rod is in position, will rest in a socket 12^a in the end of the brush 70 member 6.

The brush member may be constructed of paper pulp, the same being properly treated so as to be water proof.

Instead of forming the socket 9 in the 80 brush member 6, the perforation 10 may extend entirely through the member and the elasticity of the rubber of the member will permit the member to move over the extension 4 and the softness of the rubber of the member will permit the head 12 of the rod 85 to become embedded in the member and prevent injury to the teeth or soft parts of the mouth by the head 12, in which case the socket 12^a may be omitted. 90

The frictional engagement of the member 6 with the extension 4, together with the rectangular cross-section of the rod, will prevent rotation of the member relatively to the handle and brushing elements will 95 always be presented at the proper angle.

The extension 4 may be of circular cross-section, as shown in Fig. 3, and the frictional engagement of the member with the extension may be relied upon to prevent rotation of the member. 100

In the modification illustrated in Fig. 4, I show that portion at least, of the extension which enters the member as of non-circular cross-section to prevent turning of the member relatively to the handle. In Fig. 4, I have also illustrated the member 6 as of the usual form and material, such as bone, ivory, hard rubber, celluloid, etc., and with the usual bristles carried thereby. 105 110

I desire to have it understood that the rod may be made of a shape other than rectangular, if desired.

The head 12 of the rod may be constructed 5 of a material, such as celluloid, which will not cause injury to the mouth, or it may be covered by a cap 12^b of soft rubber or other suitable material, as shown in Fig. 5.

When it is desired to remove the member, 10 the nut is rotated so that the rod is released therefrom, thereby permitting the rod to be withdrawn from the handle, and allowing of the removal of the brush member.

The brush member 6 is small and inexpensive, and may, if desired, be discarded 15 after a single use, in which case absolutely sanitary conditions will obtain, and there will be absolutely no danger of transmitting germs to the mouth, or two members 6 may be employed, one of which may be sterilized while the other is in use.

In my construction it is possible to so manipulate the bristles as to render it easy 20 to clean the teeth on the inside. This is especially so in view of the peculiar shape which I give to the tubular extension 4. With the old style brush this is impossible, and it has been very difficult to clean the teeth on the inside.

25 In accordance with the provisions of the patent statute, I have described the principle of my invention together with the apparatus which I now consider to represent the best embodiment thereof, but I desire it understood that my invention is not confined 30 to the particular form of apparatus herein

shown and described, and, therefore, I claim broadly the right to employ all equivalent instrumentalities coming within the scope of the appended claims, and by means of 40 which objects of my invention are attained, and the new results accomplished, as herein set forth, as it is obvious that the particular embodiments herein shown and described are only illustrative of some that can be employed to attain these objects and accomplish these results.

Having now described my invention, what I claim as new and desire to secure by Letters Patent is:—

50 A tooth brush comprising a tubular handle, a tubular member removably carried thereby and extending forwardly therefrom, said member being bent slightly intermediate its ends to form an obtuse angle, a brush head carried by said member, and means for locking said brush head against movement relatively to the handle, said means comprising a flattened member removably carried by the handle and engaging the brush head, said flattened member passing through the tubular handle and the tubular member and that part passing through the tubular member being carried so as to bring a flattened face thereof against the inner wall of 55 the tubular extension.

60 This specification signed and witnessed this 17th day of January, 1919.

LEO E. EVSLIN.
